UNITED STATES PATENT OFFICE.

HOWARD A. FLOGAUS, OF DETROIT, MICHIGAN, ASSIGNOR TO RALPH L. SKINNER, OF DETROIT, MICHIGAN.

PISTON CONSTRUCTION.

Application filed August 31, 1928. Serial No. 303,188.

With present-day, high-compression, internal-combustion engines it is important to permit the rapid escape or dissipation of the high degree of heat developed in the engine-cylinders, and it has been found to be desirable for this and other advantageous purposes, such as light weight of reciprocating parts, to employ pistons made of aluminum or aluminum alloys because of their comparatively high 10 coefficients of heat conduction.

Such pistons, however, expand much more readily and rapidly than do the cast-iron cylinders in which they reciprocate, and, accordingly, attempts have been made to reduce 15 their expansion characteristics by mounting their skirts, at least in part, on metal bars of small heat expansion properties, but even this expedient does not overcome the undesired excessive or objectionable expansion qualities of the pistons.

If the pistons are fitted in their cylinders with sufficient clearance or looseness to allow for the differences in heat expansion properties of the pistons and cylinders, then the pistons will slap in their cylinders, especially 25 when the operation of the engine is first started, and, on the other hand, if the pistons are fitted sufficiently closely to avoid such objectionable noisy slapping, the pistons, 30 by reason of their quick initial enlargement, are likely to seize the cylinders and become unmovable therein with resulting serious damage to the engine, or, if the actual seizure does not occur, the pistons become detrimentally scuffed or roughened.

The permissible tolerance between a too-close fit and an adequately free piston-slapping fit is so small as to be substantially impossible of attainment under ordinary manufacturing or mass production conditions.

The result is that the engine manufacturers err on the safe side by making the piston clearances enough to avoid the pistons from becoming anchored or fixed in their cylinders by reason of their material differences in heat expansion.

In this connection, it may be borne in mind that, when the engine is first started, the heat of the hot exploded gases is transmitted directly to the pistons and they enlarge comparatively rapidly, but the cylinders are surrounded by cooling-jackets, usually filled with water, and, accordingly, the cylinders cannot expand as readily by reason of the cooling effect exerted on them by such encasing

bodies of water, whose temperature must be raised in substantial measure before the cylinders can fully respond to the heat tending to expand them.

My invention relates to novel and improved cushioning means for the pistons to eliminate any disagreeable audible noises arising out of their rocking movements on their piston-pins into contact with the cylinder-walls.

Owing to the changes of angularity of the 60 piston-rods, whose one end reciprocates and whose other end rotates, there is a decided tendency for their pistons to rock more or less noisily or audibly into hammering contact with the opposite walls of their cylinders, and 70 it is the main and leading purpose of this invention to cushion such movements of the pistons in the most approved fashion to remove or reduce such noises, whereby to provide a quiet running engine with pistons sufficiently loosely fitted in their cylinders to 75 avoid the dangerous results of too tight fits.

To this end, in the preferred embodiment 80 of the invention, a light, flexible, leaf-spring is mounted in each piston in such manner as to obtain the best results, such spring being attached at its ends to the piston and to the associated connecting-rod at points highly favorable to the production of the required effects.

In the accompanying drawing such an embodiment of the invention has been illustrated in detail, and in its two views, like reference numerals have been employed to designate the same structural parts.

In this drawing:

Figure 1 is a central, longitudinal section on line 1—1 of Figure 2 through one cylinder of an internal-combustion engine in which the piston is supplied with the cushioning or dampening means; and

Figure 2 is a transverse or horizontal section on line 2—2 of Figure 1.

Referring to this drawing, the internal-combustion engine-cylinder has been denoted by the reference numeral 11 and the companion piston which reciprocates in it in the customary manner has been characterized 12, such piston having a head and a skirt, as is usual, and a plurality of piston-rings 13, 13.

The piston is rockingly mounted on a hollow piston-pin 14, the ends of which oscillate in suitable bearings 15, 15 in the piston, the upper-split end of the associated connecting-rod 16 being fixedly clamped on the cen-

tral portion of the piston-pin by means of a screw 17, all of which is the common way of connecting the specified elements together.

The skirt of the piston, however, internally has a pair of registering bosses 18, 18, integral therewith and apertured in alignment to receive a hinge-pin rivet 19, the enlarged heads 21, 21 of which are accommodated in countersunk cavities 22, 22 extended 10 inwardly from the outer surface of the piston.

Rockingly mounted on such rivet hinge-pin is the end loop or eye 23 of a multi-leaf, bowed or arched spring 24 extended around over the top of that upper portion of the 15 connecting-rod encircling the piston-pin, the other or opposite end of the spring having a like or similar eye or loop 25 similarly mounted on a hinge-pin 26 carried by spaced ears or lugs 27, 27 of a suitably-shaped clip or 20 bracket 28 apertured to receive the shank of the screw 17 and firmly and securely clamped between the head of the latter and the adjacent face of the connecting-rod head.

In the present instance, the side of the 25 piston is cut away at 29 to provide space for the movement of the adjacent end of the spring, although in many installations such mutilation of the piston is not necessary.

The spring is put into place, under compression, so that its two ends normally tend to 30 separate, and this capability is employed to cushion the rocking or turning movements of the piston on the piston-pin, so that as the piston tends to swing on such pin into ham- 35 mering engagement or contact with the piston wall, the force of such blow is sufficiently absorbed or neutralized by the action of the spring that all objectionable or annoying noise or sound is quite overcome.

One problem to be solved in providing a 40 construction of this character is to so design and arrange the cooperating elements that the spring can be of such size and length as to give it a degree or measure of resiliency 45 which will assure its long life although undergoing repeated flexures with great rapidity.

I have found that a comparatively long 50 spring of relatively great flexibility, as contrasted with a shorter spring of corresponding increased rigidity, not only will successfully withstand the required multiplicity of rapidly recurring flexures or bending actions, but such a spring, in addition, permits of its attachment or mounting in place in 55 such a manner as to secure a greater leverage action on the piston.

The two characteristics or properties, therefore, permit the use of a spring in the specified relation which performs its func-

tion to the best advantage and the spring is 60 capable of successfully withstanding or undergoing the quickly-occurring bending actions throughout a surprisingly long period.

This result, in the present embodiment of the invention, is accomplished by securing the 65 two ends of the spring to the piston and to the connecting-rod respectively on opposite sides of and at points well below the axis of the piston-pin, such arrangement enabling or allowing the use of a spring of such length 70 that its flexibility meets the requirements essential to long life and satisfactory operation, and the action of the spring on the piston is sufficiently below such axis as to insure a substantial leverage of the spring on the piston 75 throughout the range of rocking or oscillatory movement of the connecting-rod.

Although one embodiment only of the invention has been illustrated and described, it will be apparent to those skilled in this art 80 that it is susceptible of various incorporations in physical form, all including or containing the fundamental principles of the invention, as defined by the appended claims.

It will be understood also that the shock-absorbing or cushioning spring in addition tends to remove or reduce any noises likely to otherwise occur by reason of undue looseness or play of the piston-pin in its bearings, and this will be true also in those constructions wherein the connecting-rod turns on the 90 piston-pin.

I claim:

1. The combination of a cylinder, a piston reciprocatory in said cylinder, a connecting-rod adapted to be connected to a crank-shaft, a piston-pin rockingly mounting said piston on said connecting-rod, said piston at one side of and below the axis of said piston-pin having internal registering bosses integral therewith, a hinge-pin supported by said bosses, an arched leaf-spring extending over said piston-pin and rockingly mounted at one end on said hinge-pin, and means rockingly connecting the other end of said spring to said connecting-rod on the opposite side of said piston-pin axis, said spring cushioning the swinging movements of said piston on said connecting-rod and thereby eliminating objectionable audible piston noises. 100

2. An internal-combustion engine piston having a pair of integral internal registering bosses on its skirt at one side of and below its piston-pin axis and adapted to support a securing pin of a piston-cushioning spring. 110

In witness whereof I have hereunto set my hand.

HOWARD A. FLOGAUS.
